UNITED STATES PATENT OFFICE.

HARRY H. SCHROYER, OF CHICAGO, ILLINOIS, ASSIGNOR TO THE ACME SUPPLY COMPANY, A CORPORATION OF ILLINOIS.

ACCORDION-PLAITED VESTIBULE-DIAPHRAGM.

1,123,397.

Specification of Letters Patent.

Patented Jan. 5, 1915.

Application filed April 8, 1912. Serial No. 689,357.

To all whom it may concern:

Be it known that I, HARRY H. SCHROYER, a citizen of the United States, and a resident of the city of Chicago, in the county of 5 Cook and State of Illinois, have invented certain new and useful Improvements in Accordion - Plaited Vestibule - Diaphragms; and I do hereby declare that the following is a full, clear, and exact description of 10 the same, reference being had to the accompanying drawings, and to the numbers of reference marked thereon, which form a part of this specification.

Railway vestibule diaphragms are frequently constructed of strips of fabric—for example, cotton belting—superposed one upon another and the edges stitched, riveted or staple, or otherwise permanently secured together in pairs to afford accordion plaits 15 when the diaphragm is extended and secured to the face plates. Owing to the hard service to which such structures are subjected, it is not infrequent that the diaphragms become injured or torn, and in consequence, 20 it is very desirable to afford a construction permitting quick, easy and satisfactory repair. Heretofore, where the fabric strips were permanently secured edge to edge by rivets, staples or sewing, it has been necessary to remove the diaphragm wholly 25 from the vestibule to permit such repairs to be made, thus necessitating considerable expense for labor, and inconvenience and delay.

The object of this invention is to afford a construction whereby any of the strips of fabric forming the diaphragm, may be removed from the structure without necessitating the removal of the diaphragm from 30 the car, or disturbing any other part of the diaphragm than that portion to be repaired.

It is an object of the invention also to afford a construction wherein the alternate edges of the strips forming the diaphragm 45 are detachably connected together by releasable clamps, which act not only to hold the edges of the diaphragm strips in suitable engagement, but as well affords a reinforcement and support for the diaphragm. 50 It is also an object of the invention to afford a construction of the class described, adapted for use on diaphragms of any kind

and to permit of quick and satisfactory repair, thus indefinitely extending the life of the diaphragm and greatly reducing the 55 expense of the same.

It is, of course, an object of the invention to afford an exceedingly strong, simple and durable diaphragm, capable of being constructed or repaired without expert assistance.

The invention (in a preferred form) is illustrated in the drawings and hereinafter more fully described.

In the drawings: Figure 1 is a vertical 65 transverse section of a diaphragm embodying my invention. Fig. 2 is an enlarged, fragmentary section taken on line 2—2 of Fig. 1. Fig. 3 is a fragmentary detail view similar to Fig. 2. Fig. 4 is an enlarged section on line 4—4 of Fig. 2. Fig. 5 is an enlarged section on line 5—5 of Fig. 2, and illustrating the corner or shoulder construction of the diaphragm. Fig. 6 is an enlarged inner face view of the inner angle 75 strip. Fig. 7 is a side elevation thereof. Fig. 8 is an inner face view of the outer angle strip. Fig. 9 is a transverse section taken through the leg of a diaphragm of the type set forth in my prior Patent 1,063,697, 80 issued on the 3rd day of June, 1913, for “car vestibule diaphragms,” and illustrating a similar type of diaphragm.

As shown in the drawings: 1, indicates the diaphragm face plate, and 2, the vestibule face plate, which may be constructed as usual, and between which is secured the diaphragm in a familiar manner. Said diaphragm illustrated in Figs. 1 to 5 inclusive comprises strips of fabric such as 90 cotton belting, shaped or cut and fitted to form the two legs, shoulders, and top of the diaphragm. Said strips in the accordion plaited construction illustrated in the drawings, are indicated by 3, 4, 5, 6, 7, and 8 95 respectively, and are arranged adjacent one another, and the edges thereof are engaged together in pairs to afford the accordion plaits. For the purpose of rigidly (but releasably) securing said diaphragm sections 100 or strips together at the corresponding edges, releasable clamps are employed. These comprise an inner acute angle strip 9, having sharp barbs or projections 10,

punched outwardly to engage in the fabric near the edges of the strips. Said acute angle strips 9, are arranged between said edges with the vortex of the angle directed 5 outwardly and substantially flush with the edge of the strip, and inclosing said edges and angle strip is an outward angle strip 12, which fits over said edges and is engaged in place by means of bolts 11, 10 which extend therethrough and thread into the nuts 13, in the inner angle strip. As shown, said clamping members may be constructed in short lengths, but, as shown, are constructed of the full length of the leg, 15 and serve to bind the edges of the strips together for the entire length of the leg very firmly. The edges of the strips at the top of the diaphragm are similarly secured together by means of clamping members, the 20 outer of which, indicated by 15, is curved downwardly at its ends to form the shoulders of the diaphragm and articulated with the upper end of the leg clamps in overlapped relation by means of one of said 25 bolts 11. The inner clamping member 16, is engaged as before described, between the edges of the strips.

As shown, a metallic hood is provided over the top of the diaphragm and extending well 30 onto the shoulders. For this purpose, metallic plates 17, are shaped by stamping or otherwise, to afford an attaching flange 18, adapted for engagement to the face plate by means of the binding plate 19, or angle 35 bar 20, whereby said edges of the diaphragm are secured to the face plates. The lower or free edge of one of said metallic plates extends downwardly into the diaphragm and the free end 21, thereof is flanged or turned 40 upwardly at an angle, as shown in Figs. 2 and 3, and secured on the opposite side of said plate and between the member 15, and one of the aforesaid strips, is a similar plate 22, which curves outwardly to afford a convex lower surface, and at its lower end extends downwardly to near the angle formed by the lower edge of the first described plate or sheet, said plates together forming 45 a metallic gutter, the extremities of which 50 extend onto the shoulders of the diaphragm approximately to the legs to discharge free from the diaphragm legs. This metallic gutter may also be quickly removed for repair or replacement by the removal of the 55 clamping members, and in consequence, the entire construction may readily be knocked down or dis-assembled when required, or any individual strip removed therefrom or inserted therein without disturbing any of 60 the remaining structure.

Of course, with diaphragms constructed as illustrated in Fig. 9, in which two strips of fabric of substantially double the width of the strips forming the accordion plaits here- 65 tofore described, are bent to U shape in cross

section arranged side by side, and but a single pair of edges is afforded around the diaphragm, requiring such a clamp. The outer edges of said strips are, of course, connected with the respective face plates. In 70 this construction, the same facility of repair is afforded, and the same ease in assembling the device in place.

Of course, it is to be understood that details of construction may be varied. I do 75 not purpose, therefore, limiting the patent to be granted on this application, otherwise than necessitated by the prior art.

I claim as my invention:

1. A vestibule diaphragm embracing a 80 plurality of strips of fabric, a V-shaped clamp extending along the inside and outside edges of adjacent strips, and bolts adjustably connecting said clamps to bind the strips together in angled relation at their 85 edges.

2. A diaphragm comprising strips of fabric secured at their edges in angled relation, interfitting clamps and bolts connecting the same affording adjustable binding means for 90 said strips.

3. A vestibule diaphragm comprising strips of fabric, inner and outer complementary clamps engaging the same together at their edges, and barbs on said clamps adapted 95 to grip the fabric securely.

4. A diaphragm of the class described comprising flexible strips, V-shaped interfitting clamps releasably engaging the same together at their edges affording accordion 100 plaits and bolts affording adjustable connections between said clamps.

5. A diaphragm comprising strips of fabric faced together and extending around the diaphragm, clamps releasably engaging the 105 edges together in pairs, and embracing inner acute angle strips arranged between the edges of the strips, outer acute angle strips engaging over said edges and said strips, bolts extending through said angle strips 110 and between the edges, and rigidly engaging the same together, and barbs or projections on one of said angle strips adapted to engage in the fabric to assist in gripping the 115 same in place.

6. A device of the class described embracing complementary serrated releasable clamps, and flexible strips engaged at their edges between said clamps producing a dia- 120 phragm.

7. In a diaphragm of the class described strips of fabric, a clamp adapted to engage thereover to inclose the edges thereof, a second clamp adapted to engage the opposite faces of said strips at the same edges and to co-act with said first clamp to bind said edges together and means unjustably and releasably engaging said clamps together. 125

8. In a device of the class described flexible strips, co-acting inner and outer clamps 130

adapted to bind the same together at the edges, and hinged connections between certain pairs of said coacting clamps.

9. In a device of the class described co-
5 acting complementary acute angled clamps, and fabric and metal troughing strips en-
gaged therebetween affording a pleated ves-
tibule diaphragm.

10. In a device of the class described co-
10 acting complementary releasable clamps.

fabric engaged therebetween and a pintle af-
fording hinged connection between certain
like clamp members.

In testimony whereof I have hereunto sub-
scribed my name in the presence of two sub- 15
scribing witnesses.

HARRY H. SCHROYER.
